UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

STRAIN INSULATOR.

Application filed April 10, 1919. Serial No. 289,089.

To all whom it may concern:

Be it known that I, ARTHUR O. AUSTIN, a citizen of the United States, and resident of Barberton, in the county of Summit 5 and State of Ohio, have invented certain new and useful Improvements in Strain Insulators, of which the following is a specification.

My invention relates to strain insulators, 10 more particularly adapted for high tension purposes, and one of the objects of my invention is to provide an improved strain insulator of this character which is easy to align and assemble, with parts having 15 clearance to increase the leakage path, and also to produce an insulator which is simple, durable and reliable in construction, and effective and efficient in operation. Other objects of my invention will appear 20 hereinafter.

In the accompanying drawings—

Fig. 1 is a view in elevation of a strain insulator construction embodying my invention.

Fig. 2 is a view of said insulator taken 25 from the same position as Fig. 1, showing the body of insulator material in section.

Fig. 3 is a transverse view partly in section on line 3—3 of Fig. 1.

Fig. 4 is a slightly modified form 30 constructed so as to adapt it for use in series with one or more of its kind.

Fig. 5 is a view in elevation of a modified form of strain insulator embodying my 35 invention; and

Fig. 6 is a sectional view showing additional spacing means applied to the construction of Fig. 5.

The structure shown in the drawing which 40 illustrates an embodiment of my invention is designed more particularly for use in connection with high tension systems of distribution of power, and is intended to be used wherever strain insulators are used, 45 such for instance, as the insulating of guy-wires or the dead-ending of cables.

In the structure shown I provide an elongated body A of insulating material, such 50 as porcelain, which has a plurality of grooves or channels 1 in its surface, these grooves being formed by a plurality of spaced ribs or flanges 2, running longitudinally of the insulator body and disposed substantially radially with respect to the

longitudinal axis of said insulator body. 55 Some of these grooves, as will be noted more particularly by reference to Fig. 3, are somewhat deeper than the remaining grooves, and the deeper grooves are disposed substantially diametrically opposite. In my 60 preferred construction I provide four of these deeper grooves, which are disposed substantially ninety degrees apart, so that they may be said to be disposed in pairs at right angles. The insulator body also 65 has a pair of holes 3, one hole corresponding to each pair of diametrically opposed grooves, so that these holes 3 open through from one groove to the other groove diametrically opposed therefrom. Thus the 70 axes of the holes 3 are at substantially right angles with respect to each other.

These holes, of course, are spaced apart 75 so that there is a body or quantity of insulating material between them, and are also positioned at some distance in from the ends of the insulator body A. The structure also has a pair of loop terminal members extending in opposite directions from said insulator body A and beyond the ends thereof, 80 to which terminals are attached the guy-wires or other devices with which the insulator is to be used. In the structure shown in Figs. 1 to 3, these loop terminals are composed of several parts connected together. 85 A rod 5 for each terminal is bent into a V-shape, substantially as shown in Fig. 2, and both rods are passed through the holes 3, as shown, and pointed or directed in opposite directions with respect to each other. 90 Each rod 5 passes through or is looped through the hole 3 which is farthest from the end toward which the ends of the rod are pointed, thus interlinking or interlocking the loops with respect to each other. These rods project radially, as shown clearly in Fig. 2, somewhat beyond the flanges or ribs 2 of the insulator body, and are threaded on their ends. The remaining portion of 95 each terminal loop in the present structure is formed by the members or bars 6. One of these bars or members 6 of each terminal enters each of the opposed grooves of a pair and rests at 7 against the bottom wall of said groove at a considerable distance from the end of the insulator body, and this corresponding end of each of the members 6 is turned outwardly angularly at 8 and pro-

vided with a hole through which the corresponding end of the V-shaped rod passes. Each end of the V-shaped rod 5 has a nut 9 threaded onto it to hold the member 6 and bar 5 connected together in relative position. A lining 10 of some soft metal, such as lead, is sometimes provided for the purpose of affording a relatively soft seat for the ends 7 and V-shaped bars 5 so that they 10 will adjust themselves more readily to the irregularities in the porcelain.

The reason for permitting the ends 7 of said bars or members 6 to rest against the body of the insulator is to prevent any great 15 amount of relative movement between the insulator body and the terminal loops, and also to prevent the loop from collapsing or straightening out, so to speak, when strain is applied thereto. These members or bars 20 begin at the ends 7 to turn or curve outwardly in opposite directions so that as the member 6 leaves the end of the insulator body, it will be noted that there is a comparatively wide space 11 between the bars 6 and the bottom wall of the grooves 1. This spacing extends substantially back to the ends 7 of the members 6, which are a considerable distance in from the ends of the insulator body. These spaces 11 thus 25 serve as comparatively wide air gaps and greatly increase the insulating qualities, of the structure. It also lengthens the leakage path along the surfaces of the grooves 1 and other surfaces of said insulating body 30 between one loop terminal and the other. It will be noted also that this advantage is also enhanced by allowing considerable space between said rods 5 and member 6, and the surfaces of the flanges or ribs 2, thus 35 increasing the surface leakage in this direction 40 also.

The bars or members 6 project considerably beyond the ends of the insulator body and may be attached to the guy wires in any desired manner. In the construction shown 45 their outer ends are brought into contact or engagement with each other, and are held together by the bolts and nuts 13. The end portions 14 extend somewhat beyond the clamping bolts and nuts 13, and are spaced apart to form a clevis, and a bolt 15 is passed through these outer extreme end portions and held in place in any suitable manner by a cotter pin 16. The guy wires 17 50 may be attached to this clevis in any suitable manner, such as by passing the guy wires 17 through the clevis in the form of a loop, as shown more clearly in Fig. 1, and the two portions of the loop held together by a band or ring 18.

In Fig. 4 are illustrated two of the improved strain insulators connected in series so as to increase the total insulating effect. It would, of course, be possible simply to connect the clevis of one terminal of one in-

sulator with the clevis of one terminal of another insulator and so provide a series arrangement, but I prefer instead of this to eliminate one of the clevises from each insulator and simply form a double loop, so 70 to speak, between the two insulating bodies A. This double loop, so far as each insulator itself is concerned, is the same as shown in Figs. 1 to 3, but instead of bringing the outer ends of the member 6^d together to form a clevis, the members 6^d are formed on both ends alike, and these ends are connected, as in Figs. 1 to 3, to the V-shaped rods or members 5, as clearly shown in Fig. 4. 75

The portions of these bars or members 6^d, between the ends of the adjacent insulators, are preferably straight and parallel with respect to each other, and are of sufficient length to properly space the insulators apart. The end portions of these bars or members 6^d are curved away from the bottom wall of the grooves exactly as in the case of the structure of Figs. 1 to 3, so as to 80 provide the air gaps 11. In this manner, and by means of this construction, any number of insulators may be placed in series in accordance with the particular requirement.

The structure shown in Fig. 5 is a modification of those shown in the preceding figures, particularly in the manner of constructing the loop terminal members. The insulator body A is preferably constructed in the same manner, as in the preceding figures, but the terminal loops are formed by pieces of cable 20, or other material suitable for the purpose. These lengths of cable 20 are passed through the holes 3 in the insulating member A in the same manner as the bars 5 in the preceding figures, and are bent into a comparatively long U or V-shape, and their ends attached in any suitable manner to a cross member 21. In the construction shown the ends of these cable loops are doubled over and wedged into sockets 22 in said cross member, and the socket may then be filled with solder or other material, but this construction obviously may be modified to suit requirements. The cross members 21 may be provided with clevises 23, as in the preceding figures, to which clevises the loop ends of the guy wires 17 may be attached. In anchoring the outer ends of the cable loop terminals 20 they should be spaced far enough apart at the ends of the insulator body, so as to provide the air space or air gap 11 between said cables and the bottom and side walls of the grooves 1 of the insulator body. 110

In the form shown by Fig. 5 it may be desirable to space the cable and insulator farther apart, and if so, a spacing member or sleeve 23, as shown by Fig. 6, may be employed, which is placed in position between 115 120 125

the ribs 2 before the ends of the cable loops are secured to the cross member 21.

With the construction shown by Figs. 1 to 4, the insulating members A and the connecting and terminal bars 6, 6^a, are held rigidly in alinement, the spacing distance 11 being maintained under all conditions so that the best insulating condition is always insured.

19 I claim:—

1. The combination with an elongated body of insulating material having a plurality of holes extending therethrough in a direction transverse to the direction of greatest length of said body and spaced from the ends thereof, of terminal members passing through said holes and extending in opposite directions beyond the opposite ends of said body, and means for spacing the extending portions of said terminal members from the lateral surface of said insulating body adjacent the ends thereof.

2. The combination with an elongated body of insulating material having a plurality of holes extending therethrough in a direction transverse to the direction of greatest length of said body and spaced from the ends thereof, of terminal members passing through said holes and extending in opposite directions beyond the ends of said body, and means for spacing the extending portions of said terminal members from the lateral surface of said body adjacent the ends thereof to provide air gaps between said body and said terminal members.

3. The combination of an elongated body of insulating material having a plurality of ribs extending longitudinally thereof and forming grooves therebetween and having holes extending through said body transversely thereof and opening into said grooves at an angle with respect to each other, and terminal members looped through said holes and extending along said grooves and beyond the ends of said body, means for spacing said terminal members from the walls of said grooves adjacent the ends of the body to provide air space between said terminal members and said body.

4. The combination of an elongated body of insulating material having a plurality of spaced longitudinal ribs or flanges extending longitudinally thereof and forming grooves therebetween and having a pair of holes extending through said body transversely to the direction of greatest length thereof and at a distance from the ends of said body and opening into said grooves at an angle with respect to each other, and a pair of terminal members having portions passed through said holes and leading longitudinally of said grooves away from and beyond the ends of the body in opposite directions, means for spacing said terminal members from the walls of the grooves ad-

jaacent the corresponding ends of said body to provide air gaps between said terminal members and said body.

5. The combination with a longitudinally ribbed insulating member having transverse holes therethrough at right angles to each other, and terminal members looped through said holes and extending beyond the ends of said insulating member in the direction of the grooves formed by said ribs, means for clamping the terminal members against the body of the insulating member at a distance in from the end thereof and means for spacing said members from the bottoms of the grooves at the end of the insulating member.

6. An insulator comprising a plurality of longitudinally ribbed insulating members, and terminal and connecting members linked together through said insulating members and means for rigidly clamping said members in the grooves formed by the ribs, the terminal and connecting members being formed to extend entirely clear of the insulating members at and near the ends thereof.

7. An insulator comprising a plurality of longitudinally ribbed insulating members, and terminal and connecting means attached thereto, comprising bars which engage the insulating members in opposite grooves formed by the ribs at a distance from the ends of the insulating members and are spaced from surfaces of these members at and near the ends thereof, and means for clamping opposite bars against the insulating members.

8. An insulator comprising a plurality of elongated insulating members, and terminal and connecting means attached thereto in longitudinal alinement, said means comprising bars engaging said members at a distance from the ends but extending beyond the ends and spaced from said members at and near the ends, and clamping means for engaging oppositely disposed bars and clamping them against the members.

9. In an insulator, the combination with a perforated elongated insulating member, of connecting means looped through a perforation in said insulating member and comprising a pair of connecting members arranged to engage the insulating member adjacent the opposite ends of said perforation only but spaced from all other parts of its surface, said connecting members extending beyond one end of the insulating member, a connecting bolt extending through said perforation and attached to said pair of connecting members to hold them in place, and a pad of yielding material extending through said perforation under said bolt and disposed between said pair of connecting members and said insulating member.

10. An insulating member comprising an elongated body with longitudinal ribs providing substantially straight grooves therebetween, together with attaching means secured to said insulating member placed in the grooves between said ribs and spaced from said elongated body and ribs adjacent the end of said body to increase the length of leakage path with a given length of insulator.
11. An insulator comprising an elongated body with radial insulating blades, and interlocking tension members separated by said blades, said members being in contact with said insulator body near the longitudinally central portion of the insulating member only and extending in opposite directions from their respective points of contact between said blades past the opposite ends of said body.
12. An insulator comprising interlocking tension members, and an elongated insulator body with radial projecting longitudinally extending insulating vanes positioned between said tension members, said members being free from the vanes and body portion near the ends of said insulator to increase effective insulation.
13. The combination with a dielectric member, of terminal members extending in opposite directions therefrom, said terminal members comprising outwardly bowed bars having inwardly projecting ends engaging said dielectric member at points spaced from the ends thereof for spacing the terminal members, extending in each direction, from the lateral surface of said dielectric member to increase the leakage path about the ends of said dielectric member.
14. In combination, an elongated dielectric member having longitudinally extending ribs, a pair of terminal members passing through openings in said dielectric member and extending in opposite directions from said dielectric member and positioned in the grooves between said ribs, and means for spacing portions of said terminal members from the bases of said grooves, at each end of said dielectric member, said spacing means comprising inwardly projecting portions on said terminal members engaging said dielectric member at points spaced from the ends thereof.

In testimony whereof I have signed my name to this specification, on this 3rd day of April A. D. 1919.

ARTHUR O. AUSTIN.
